CENTERING DEVICE

William Walter Hartman, Los Angeles, Calif.

Application February 9, 1933, Serial No. 189,674

2 Claims. (Cl. 166—4)

My invention relates to an improved centering device, of the type using outwardly bowed springs for centering pipe, tubing, or the like, or rods of any sort, in a hole.

5 While my means or device is of general utility wherever centering of the foregoing type is desired, nevertheless, a field of especial utility arises in centering either slotted or unslotted pipe in a gravel packed well.

10 In gravel packing a well the process briefly is to complete the hole with permanently installed steel casing of moderately large diameter, to a point just above the strata that is to produce the desired product, usually oil, water or gas. The 15 drilling then proceeds through the center of the casing into this producing strata to the desired depth, often several hundred feet, and thereafter this hole is reamed to a diameter substantially larger than the bore of the casing, along the 20 entire length of the hole below the casing. It is into this reamed hole that the strainer pipe is lowered, and then sufficient coarse gravel is fed into the well to completely fill the space between the strainer pipe and the walls of this reamed hole.

25 The object of all this is that in the finished well the fluid will pass from the fine sands or other formation comprising the producing strata, thru the gravel envelope thus supplied, into the strainer pipe, from whence it rises to the top of the 30 well. The purpose of the gravel pack is to act as a filter and hold back the fine sands or particles in the producing strata, to thereby prevent or retard same from clogging or filling the strainer pipe or otherwise interfering with the efficient operation of the well. But in order that the supplied envelope of gravel can properly protect the strainer pipe the latter should be centralized in the hole to insure the distribution of a uniform thickness of gravel all around the strainer 40 pipe.

It is in the process of thus centralizing the strainer pipe, or any other pipe embedded in gravel, that my centering device finds its field of special utility.

45 In the process of completing a well in the foregoing manner, it occasionally happens for various reasons, that after my centering device and the strainer pipe are immersed in the supplied gravel, it becomes necessary to pull the strainer 50 pipe and my centering device mounted thereon, up through the gravel into the casing, and thence on up through the well. Under these circumstances two series difficulties may be encountered with ordinary centering devices owing to the relatively wide springs which they use to procure good

bearing against the walls of the hole. These difficulties are, first, that such wide springs are hard to pull up through the gravel as they offer much resistance, and, second, that at the place where the device passes from the reamed hole 5 into the smaller casing, the springs must fold inward against the pipe to accommodate themselves to the reduced casing diameter, and the gravel naturally tends to be trapped between the ordinary wide flat springs and the pipe, and thereby 10 obstructs the proper folding in of such springs. This trapping of the gravel occurs mostly near the collars where the wide flat springs are close to the pipe, and where there is particularly little room for the gravel to escape, thereby producing this trapping of the gravel. All the foregoing makes it difficult both to raise the device through the gravel, and to cause it to enter the smaller casing from the reamed hole.

It is these difficulties that my improvement largely eliminates.

Broadly speaking my invention is characterized by having springs that are relatively wide where they extend out the furthest to supply the desired bearing, and that are relatively narrow where they approach the collars, or pipe, or other tubular member on which they are mounted, to thereby permit the free escape of the gravel and aid the entry of the device from the hole into the smaller casing, and also minimize the resistance in pulling the device upward through the gravel.

Other features, objects and benefits of my invention will become apparent from consideration of the attached drawing, also from the following detailed description, and from the claims.

The broad features of my invention may be applied and utilized in various ways, to suit various tastes and circumstances, it being understood that in the accompanying drawing, and in the following detailed description, I am illustrating only one preferred form of my invention, and two modifications thereof, but I am aware that still other modifications can be made without departing from the spirit of my invention, which is limited only by the terms of the claims. 45

In the drawing, like parts are designated by like reference numerals.

Fig. 1 is a front elevation showing my centering device installed in a well, the soil, producing strata and certain parts of the well being shown in section, to disclose my centering device in place.

Fig. 2 is a section through the well taken along

line X^1-X^2 , looking in the direction of the arrows, in Fig. 1.

Fig. 3 is a fragmental sectional view along line X^3-X^3 , looking in the direction of the arrows, in Fig. 1.

Fig. 4 is a fragmental sectional view along line X^4-X^4 , looking in the direction of the arrows, in Fig. 1.

Fig. 5 is a fragmental sectional view along line X^5-X^5 , looking in the direction of the arrows, in Fig. 1.

Fig. 6 illustrates the shape of the bearing member shown in Fig. 1, before the ends are folded under to embrace the springs.

Fig. 7 is a front elevation of a modification of my device, the drawing being confined to a typical fragment of the device along one spring, this being sufficient to clearly illustrate the modification.

Fig. 8 is a section along broken line X^8-X^8 , looking in the direction of the arrows, in Fig. 7, a fragment of the pipe being also included in Fig. 8.

Fig. 9 is a front elevation of another modified form of my device.

I will first describe the preferred form of my invention, illustrated in Figs. 1 to 6, inclusive.

In Fig. 1 is seen the well casing 1 installed in the upper earth formation 2, and the enlarged hole 3 reamed out in the producing strata 4, below casing 1. Pipe 5 and strainer pipe 6, are shown installed and centralized in this enlarged hole 3, the centralizing having been accomplished by my device, illustrated generally by reference numeral 7, shown mounted on pipe 6, in Fig. 1. The supplied gravel, or gravel pack, indicated by reference numeral 8, and being in general a body of uncemented gravel-like material, completely fills hole 3 up part way into casing 1, the exact height to which this gravel is carried being however, immaterial in this invention. Some of the gravel has been omitted from Fig. 1, especially around device 7, in order to aid the clearness of the illustration.

My device, in the form shown in Fig. 1, comprises the hollow cylindrical collars 9, and my special type springs 10 secured thereto. The collars 9 are spaced apart from and aligned with each other to form the axis of my device, indicated by dashed lines A—A in Fig. 1, this axis corresponding with the center line of pipe 6.

The springs 10 may be secured to collars 9 in any desired manner, as by flattening their ends at 11, see Fig. 1, and welding these flattened ends to the outside of collars 9, as indicated at 12 on the central spring on lower collar 9, in Fig. 1; or the spring ends can be inserted more or less flush in notches in the collars as will be herein-after described in connection with my modification shown in Figs. 7 and 8; or the springs can be secured to the collars in any desired manner. In fact in the rudimentary form of my invention shown in Fig. 9, the springs can be mounted on the pipe by welding them directly onto the pipe, as will be hereinafter described.

In the preferred form of my invention, the bore of collars 9 is preferably slightly larger than pipe 6, so that the device is free to rotate on, and to have limited movement lengthwise along pipe 6. This lengthwise movement along pipe 6, should, however, be in some way limited, because the length of pipe 6 may be several hundred feet, in which case it is desirable to have the centering device, or devices, 7, somewhat definitely located on pipe 6 according to

some predetermined position or distribution. For this purpose the device is more or less secured to pipe 6 in any one of various ways. This can be done for instance, by utilizing the ordinary pipe couplings 14, which are used to join successive sections of pipe 6 together, in which case my device 7 is left free to float between any two such successive couplings 14, these butting against one or the other of my collars 9 to limit the sliding of my device along pipe 6. Or, one or the other of my collars 9, preferably the lower one, may be welded, or otherwise secured to pipe 6, thereby leaving only the other collar 9 free to float lengthwise of the pipe to permit free flexing of the springs, but nevertheless securing my device to pipe 6 for reasons indicated. Or in an extremely rudimentary adaptation of my invention, illustrated in Fig. 9, one or the other ends of my springs, instead of being secured to my collars 9, could obviously be secured direct to the pipe, thus leaving one end of each spring free to slide lengthwise of the pipe, while the other end is directly secured to the pipe. The free ends could be either entirely free, or could be joined to each other by using one collar, in manner that is obvious without additional illustration.

But while my device can be secured to the pipe in any of the above described ways, or in any other desired manner, nevertheless I prefer to limit the said lengthwise movement of my device along the pipe, by providing on the pipe between my spaced apart collars 9, some sort of stop means adapted to butt against collars 9, this preferably being a ring 15, see Fig. 1, securely fastened to pipe 6, as by welding or otherwise. This mode of limiting the movement of my device on pipe 6, has the advantage that if this pipe, and my device, must be raised from hole 3 into casing 1, the stop 15 will rise and butt against my upper collar 9, and in effect pull all the springs 10 upward into casing 1. When the springs are pulled upward in this manner they naturally tend to fold freely inward against pipe 6, to accommodate themselves to the reduced diameter of casing 1, whereas if my springs were pushed upward from their lower ends, they would most likely buckle or break off, and cause general trouble. Also in lowering my centering device through the well, there are circumstances in which it functions more satisfactorily when pulled ahead by stop 15, and this therefore is my preferred mode of making the attachment.

As shown in Fig. 1, the general shape of my springs can be referred to as being bowed outwardly, by which I mean that the springs in a general way are further from the axis A—A at places intermediate of the collars 9, than they are near collars 9, and any shape that suits this condition is satisfactory for my invention, the precise shape being immaterial.

My springs 10, in the preferred form of my invention, in order to be sufficiently strong to properly center pipe 6, and yet to be relatively narrow in a general circumferential direction about axis A—A, are made of circular cross-section as indicated in Figs. 3, 4 and 5. This circular section, in addition to combining the desired circumferential narrowness with the desired strength of the springs, has the further advantage of affording excellent escape for the gravel from the pocket-like areas 16, see Fig. 1, where the springs and pipe are close together, and where the above described trapping of the

gravel behind the ordinary wide springs occurs, and in addition such round springs have the advantage that they pull up through the gravel much more easily than the ordinary wide flat 5 springs.

But in order that my springs may have good bearing against the formation 4, at the place where the bearing occurs, I provide suitable bearing members 17 on springs 10 at the places 10 where these springs extend radially furthest from the axis A—A, this place usually but not necessarily being about midway of the ends of the springs. The precise shape and mode of attaching these bearing members 17 to springs 10 can 15 vary considerably, the sole requirement being that they should be relatively wider than springs 10, this width being considered in a direction generally circumferential of the device, to give the bearing action referred to. Whether these bearing members are fastened to the inside or the outside of spring 10, is not particularly material, although I prefer to fasten them to the outside. In Fig. 1 these bearing members 17 are shown fastened to springs 10 by welding 18 applied for 20 only a limited distance between "a" and "b" near the center of member 17, the ends 19 of this member being free to slide lengthwise of springs 10 but being nevertheless secured thereto. This latter feature can be best understood by reference to Fig. 6, showing the blank form of member 17, it being understood that in finishing this 25 blank, its ends 19 are wrapped around spring 10 and then welded at 20, see Figs. 3 and 4, thus securing ends 19 about springs 10 yet leaving them free to slide lengthwise thereof. In this 30 way, springs 10 are left free to bend and accommodate themselves to variations of hole diameter as they pass along, and the bearing members 17 are also free to readily accommodate themselves 35 to the bending of springs 10, because the ends 19 of members 17 can freely slide along springs 10, even though secured thereto.

From Figs. 1, 2, 4 and 6, especially Fig. 2, it is evident that the circumferential width x of 40 bearing members 17 is relatively larger than that of springs 10, (indicated by y , Fig. 2) thereby providing the bearing action above described, combined with provision for the free escape of 45 the gravel.

In a sense members 10 and 17 can, if desired, 50 be considered as integral, and as comprising my springs, in the preferred form of my invention, illustrated in Figs. 1 and 2.

In the form of my invention shown in Figs. 7 55 and 8, my springs 10² are shown as consisting of relatively flat strips that are circumferentially wide along the bearing portion 17¹, where the springs project out furthest from pipe 6¹, and that are relatively narrow circumferentially along 60 the spring portions that approach the collars 9¹, as indicated at 25 in Fig. 7. In this form, my springs, if desired, can be made relatively thicker along the narrow portion 25, see Fig. 8, than along the relatively wider bearing portion 17¹, 65 such variation in thickness being intended to equalize the spring strength by compensating for the varying width. In this form of my invention the spring ends 26 are shown as set into notches 27 of the collars 9¹, these spring ends 70 being welded to the collars along notches 27 as indicated at 28, thereby making the spring ends 26 and collars 9¹ substantially flush inside and

outside. In Fig. 8 the stop ring 15¹ is secured to pipe 6¹ between the two collars 9¹, in manner similar to Fig. 1, so that this stop 15¹ is adapted to abut against edges 29 of collars 9¹, as best seen in Fig. 8. 5

Fig. 9 illustrates a rudimentary form of my invention, in which my springs 10² are attached direct to any suitable tubular member, such as the pipe itself, 6², the spring ends 26² being directly welded to pipe 6² as indicated at 27². In 10 this form of my invention, the upper ends of springs 10² are preferably free to slide along the pipe so as not to interfere with the flexing of the springs.

In the various forms of my invention, it is immaterial whether the direction of the springs, viewed generally lengthwise of the pipe, is straight as indicated by the middle spring in Fig. 1, or by the spring in Fig. 7, or whether the springs are spiraled lengthwise of and slightly around the 20 pipe; and it is also immaterial whether the bearing member, or bearing portion of the spring, lies exactly circumferentially about the axis of the device, or only approximately so, or even slightly tilted with reference to a true circumference; all such modifications being intended as embraced in my invention. 25

From the foregoing detailed description it is thought that the construction, mode of operation, and the various features and advantages of 30 my invention are apparent.

I claim:

1. A pipe centering device comprising in combination, two hollow cylindrical end collars in line with and spaced apart from each other, a plurality of outwardly bowed springs fastened to said collars, and bearing members on said springs at the place where the springs are bowed outward the furthest, the width of said bearing members when measured in a direction circumferential of said device being greater than the width of said springs when measured in the same manner, and the length of said bearing members being disposed for a limited distance 35 along the length of said springs, each such bearing member being fastened to its spring at a place intermediate of the ends of the bearing member and having the ends of the bearing member free to slide lengthwise of its spring. 40

2. A pipe centering device comprising in combination, two hollow cylindrical end collars in line with and spaced apart from each other, a plurality of outwardly bowed springs fastened to said collars, and bearing members on said springs at the place where said springs are bowed outward the furthest, the width of said bearing members when measured in a direction circumferential of said device being greater than the width of said springs when measured in the same manner, and the length of said bearing members extending for a limited distance along the length of said springs, each such bearing member being fastened to its spring at a place intermediate of the ends of the bearing member, and the ends of said bearing members being slidably fastened to the springs to cause the bearing members to flex substantially in unison with the springs but leaving the ends of the bearing members free to slide lengthwise of the springs as the springs and bearing members flex. 50

WILLIAM WALTER HARTMAN. 70
